POTTER'S WHEEL

Robert E. Piepenburg, 515 E. Windemere,
Royal Oak, Mich. 48073

Filed Sept. 8, 1972, Ser. No. 287,505

Term of patent 14 years

Int. Cl. D15—09

U.S. Cl. D55—1 R

Fig - 1

Fig - 4

Fig - 2

Fig - 5

Fig - 3

FIG. 1 is a perspective view showing my new design for a potter's wheel.

FIG. 2 is a top plan view of the potter's wheel shown in FIG. 1 with the seat element in an alternate position.

FIGS. 3, 4 and 5 are front, side and rear elevational views respectively of the potter's wheel shown in FIG. 1 with the seat element positioned as in FIG. 2.

I claim:

The ornamental design for a potter's wheel, substantially as shown and described.
